DESIGN FOR A COASTER WAGON

John G. Rideout, Perrysburg, Ohio, assignor to
The American-National Company, Toledo,
Ohio, a corporation of Ohio

Application December 10, 1934, Serial No. 54,382

Term of patent 7 years

To all whom it may concern:

Be it known that I, John G. Rideout, a citizen of the United States, and resident of Perrysburg, in the county of Wood, State of Ohio, have invented a new, original, and ornamental Design for a Coaster Wagon, of which the following is a specification, reference being had to the accompanying drawing, forming a part thereof.

The dominant feature of my design resides in the body portion shown in full lines in the drawing and particularly in the front end configuration thereof.

I claim:

The ornamental design for a coaster wagon, substantially as shown and described.

In testimony whereof I have hereunto signed my name to this specification.

JOHN G. RIDEOUT.
